US00D735311S

(12) **United States Design Patent**
Horiguchi

(10) **Patent No.:** US D735,311 S
(45) **Date of Patent:** ** Jul. 28, 2015

(54) **EXHAUST CLEANER FOR FLUID PRESSURE DEVICE**

(71) Applicant: **Hiroyuki Horiguchi**, Tsukubamirai (JP)

(72) Inventor: **Hiroyuki Horiguchi**, Tsukubamirai (JP)

(73) Assignee: **SMC Corporation**, Chiyoda-ku, Tokyo (JP)

(**) Term: **14 Years**

(21) Appl. No.: **29/478,531**

(22) Filed: **Jan. 6, 2014**

(30) **Foreign Application Priority Data**

Aug. 30, 2013 (JP) 2013-020069

(51) **LOC (10) Cl.** 23-04

(52) **U.S. Cl.**

USPC **D23/365**

(57) **CLAIM**

The ornamental design for an exhaust cleaner for fluid pressure device, as shown and described.

DESCRIPTION

FIG. 1 shows a front view of an exhaust cleaner for fluid pressure device showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a bottom, front and left side perspective view thereof;

FIG. 8 shows a top, front and right side perspective view thereof; and,

FIG. 9 shows an enlarged cross-sectional view thereof, taken along line 9-9 in Fig. 1.

The portions of the design shown in broken lines in FIGS. 1-9 are for the purpose of illustrating the environment only and form no part of the claimed design.

1 Claim, 5 Drawing Sheets
